UNITED STATES PATENT OFFICE.

MATHER W. SHERWOOD, OF FRANKLIN, PENNSYLVANIA, ASSIGNOR TO CHICAGO PNEUMATIC TOOL COMPANY, OF CHICAGO, ILLINOIS, A CORPORATION OF NEW JERSEY.

DRILLING-MACHINE.

1,116,138.

Specification of Letters Patent.

Patented Nov. 3, 1914.

Application filed January 10, 1914. Serial No. 811,340.

To all whom it may concern:

Be it known that I, MATHER W. SHERWOOD, a citizen of the United States, residing at Franklin, Venango county, Pennsylvania, have invented certain new and useful Improvements in Drilling-Machines, of which the following is a specification.

My invention relates generally to drilling machines and more particularly but not necessarily to rock drills of the hammering piston type.

The object of my invention is in general to provide a simple, efficient and reliable machine of this character, and in particular to improve the construction of the fluid pressure controlled means and associated parts which operate and drive the rotary drill chuck.

Another object of my invention is to provide simple and improved means for connecting together the main cylinder and front head and to combine such means with certain parts coöperating with the said fluid pressure controlled means.

Still another object of my invention is to provide a simple and efficient packing between the front head of the machine and the outer end of the drill chuck.

Other novel and advantageous features of construction and operation will be apparent from the description hereinafter given.

In the drawings Figure 1 is a central longitudinal sectional elevation of a drilling machine illustrating one embodiment of my invention; Fig. 2 an elevation thereof; Figs. 3 and 4 cross sections on the line 3—3 and 4—4 respectively of Fig. 2; Fig. 5 a detail view of the bushing between the cylinder and the head; Fig. 6 a cross section on the line 6—6 of Fig. 1 showing the packing at the front end of the drill socket; Fig. 7 a longitudinal section of the lower end of the main cylinder and the front head and drill socket on a larger scale than Fig. 1, and Fig. 8 a detail section illustrating one of the pair of modified form of clamping bolts employed.

Referring to the particular embodiment of my invention illustrated in Figs. 1 to 4, my drilling machine comprises a cylinder 1,

a piston 2 reciprocable therein, a striking piece or anvil 3, a front head 4, a bushing 5 interposed between the cylinder and the front head, a rotatable drill socket 6, drill bit or steel 7, the side bolts 8 and cushion springs 9 on said bolts, together with fluid pressure mechanism for rotating the socket comprising a pair of pistons 10 arranged in cylinders 11 on opposite sides of the front head and having the ratchet drive connection with the drill socket as hereinafter explained. The piston is operated by motive fluid controlled by a distribution valve (not shown but contained within the casting 12) through suitable ports and passages leading to and from opposite ends of the main cylinder, but as these ports and passages may be of any suitable arrangement and as the valve may be of any suitable type well known in this art, the same need not be illustrated or described. The bushing 5 which is adapted to fit into the front end of the cylinder and also within the rotatable socket is provided with a central opening in line with the axis of the main cylinder and its piston in order to receive the anvil 3 which communicates the blows of the piston to the inner end of the drill steel or bit 7. The front head 4 is cylindrical at its outer end to receive the cylindrical front end of the drill socket which rotates therewithin. Between the front end of the socket and the annular shoulder 4^a of the front head is interposed packing which here consists, as shown in detail in Fig. 6, of a circular washer 13 of felt or the like and a flat spring 14, the construction and arrangement of this packing being such that chips are prevented from getting into the bearing between the head 90 and the drill socket or sleeve.

As stated the cylinders 11 are formed on opposite sides of the front head and the ends of these cylinders are closed by similar caps 15 which fit closely therein but are not screwed in as usual, the same being readily insertible and removable. These caps are held in place by means of yokes 16, the outer ends of each one of which are adapted to bear against the outer faces of 100

the two end caps 15 at corresponding ends of the cylinders. Each yoke fits between a pair of parallel lugs 17 having registering holes corresponding with a hole 18 in the yoke. A hollow drift pin 19 passes through the lugs 17 and the interposed yoke 16, thereby holding the latter in place. By preference the drift pin has a tapering body and a head 20 bearing against the lower face 10 of the lower lug 17.

The drift pins are made hollow in order to permit the side bolts 8 to pass therethrough, thereby providing a compact construction. The cushion springs 9 which are coiled 15 around the lower ends of the bolts 8 bear at their upper end against the heads of the drift pins and at their lower ends against the nuts 21.

The drill socket is flanged at its upper end 20 and provided on its circumference with ratchet teeth 22 which are adapted to cooperate with pawls 23 mounted on and reciprocated by the pistons 10. These pawls are normally spring-pressed into engagement 25 with the ratchet teeth by means of the springs 24. In addition I provide locking dogs 25 which are spring-pressed by the springs 26 into engagement with the ratchet teeth. These dogs are movable in a plane 30 parallel with the axis of the piston and the outer ends of the springs 26 bear against the yokes 16 with the result that the dogs may be readily removed whenever the yokes are removed.

35 The opposite ends of the cylinders 11 are connected by means of the ports and passages 27 and 28 with the rear and front ends respectively of the main cylinder 11. As illustrated the ports and passages 27 will 40 admit the fluid pressure from the rear end of the main cylinder to one end of one cylinder 11, and to the opposite end of the other cylinder so as to cause one of the pistons 10 to move in one direction and the other in the 45 opposite direction. At this same time the other passage 28 which would then be at exhaust would be exhausting the pressure from the other ends of the two cylinders 11, thereby causing a reciprocation of the pistons 10 and a consequent driving of the drill socket. 50 In the present instance the side bolts 8 pass through lugs 29 on the handle socket 29 through notches in the rear or top flange 1^b of the cylinder and through similar notches 55 in the bottom or front flange 1^b although if desired holes may be provided in said end flanges of the cylinder. These bolts continuing beyond the flange 1^b pass through the lugs 17 and the hollow drift pins and 60 carry at their lower ends the cushion springs 9 as hereinbefore explained.

In Fig. 8 I have shown a modified construction according to which long side bolts 8 running the full length of the cylinder are

dispensed with. As shown these side bolts 65 30 are short bolts which merely extend through the lower flange 1^b of the main cylinder and through the lugs 17, yokes 16 and through hollow drift pins 19. The lower end of these bolts 30 are provided with the 70 cushion spring 9 already described.

I claim:

1. In a drill, the combination with a main hammer, a cylinder and its hammer, of a drill 75 chuck or socket mounted to rotate at the front end thereof, fluid pressure controlled mechanism for rotating the socket including pistons, and cylinders therefor, heads in said cylinders and yokes arranged to hold the heads in place.

2. In a drill, the combination with a main hammer, a cylinder and its hammer, of a drill chuck or socket mounted to rotate at the front end thereof, fluid pressure controlled mechanism for rotating the socket 85 including pistons, and cylinders therefor, heads in said cylinders, yokes arranged to hold the heads in place and bolts passing through the yokes.

3. In a drill, the combination with a hammer cylinder and its hammer and with the front head thereof, of bolts for securing the cylinder and head together, a drill socket mounted to rotate in said head, fluid controlled mechanism mounted in the head for 90 rotating the socket including pistons, driving connections between them and the socket, said head having a pair of piston chambers for said pistons and heads for such chambers and yokes bearing against said heads 95 for holding them in place, said bolts passing through such yokes.

4. In a drill, the combination with a hammer cylinder and its hammer and with the front head thereof, of bolts for securing the 105 cylinder and head together, a drill socket mounted to rotate in said head, fluid controlled mechanism mounted in the head for rotating the socket including pistons, driving connections between them and the socket, 110 said head having a pair of piston chambers for said pistons and heads for such chambers, yokes bearing against said heads and having central openings, and hollow drift pins in such openings, said bolts passing through 115 said pins.

5. In a drill, the combination with a hammer cylinder and its hammer and with the front head thereof, of bolts for securing the cylinder and head together, a drill socket 120 mounted to rotate in said head, fluid controlled mechanism mounted in the head for rotating the socket including pistons, driving connections between them and the socket, said head having a pair of piston chambers 125 for said pistons and heads for such chambers, said head having pairs of lugs provided with openings, yokes arranged be-

tween the lugs and having corresponding openings, the ends of said yokes bearing against the cylinder heads, and hollow drift pins in said yoke openings through which said bolts pass.

6. In a drill, the combination of a cylinder, a front head, a rotating drill socket

within the head, and a packing between the ends of the head and socket comprising fibrous material and a spring ring.

MATHER W. SHERWOOD.
